INVENTOR:
Ernest M. Wenzel,
BY
Charles Gerard,
ATTORNEY

UNITED STATES PATENT OFFICE.

ERNEST M. WENZEL, OF KANSAS CITY, MISSOURI.

WASHING-MACHINE.

1,284,511.

Specification of Letters Patent. Patented Nov. 12, 1918.

Application filed June 20, 1918. Serial No. 241,083.

To all whom it may concern:

Be it known that I, ERNEST M. WENZEL, a citizen of the United States, residing at Kansas City, in the county of Jackson, State of Missouri, have invented certain new and useful Improvements in Washing-Machines, of which the following is a full and exact specification.

The present invention relates to improvements in laundry appliances, and one of the objects in view is to devise an improved washing machine construction comprising a cover for tubs, boilers, and the like, and equipped with a washing cylinder, together with provision whereby said cover may be detachably secured to receptacles of varying types and sizes.

It is also an object of the invention to provide a washing machine construction of the character indicated and including a removable cover carrying a rotary washing cylinder rotating about an axis in approximately the plane of the cover, and provided with a removable housing for inclosing that portion of the cylinder projecting above the cover.

It is a further object of the invention to devise a neat and simple, but durable and efficient, construction of the type described which may be cheaply and economically manufactured from inexpensive material.

With these general objects in view the invention will now be described with reference to the accompanying drawing illustrating one form of embodiment of the improvements, after which those features deemed to be novel will be set forth and defined in the appended claims.

In the drawing—

Fig. 1 is a plan view of a washing machine constructed in accordance with the present invention;

Figs. 2 and 3 are central vertical sectional views, taken on the lines 2—2 and 3—3, respectively, of Fig. 1; and

Fig. 4 is an enlarged detail sectional view, representing a section taken on the line 4—4 of Fig. 1.

Referring to the said drawing in detail, this illustrates the improvements as embodied in a cover member 6, which may be constructed of any suitable material, such as sheet metal, and of any desired form or shape, the cover being illustrated in the present drawing as of circular form and

provided with a central rectangular opening 8. Upon the top or outer face of this cover is secured, as by rivets 10 or the like, a pair of angle pieces 12 extending along the opposite sides of the opening 8, and similarly secured across the ends of said opening 8 is a pair of transverse angle pieces 14.

The cover member 6 is adapted to be detachably secured to receptacles such as boilers, tubs, etc., of various types and shapes and sizes, and for this purpose I provide a set of hook bolts 16 having wing nuts 18, these bolts being adjustable along slots 20 provided therefor in the end portions of the angle pieces 12 and outer margins of the cover member 6. The drawing shows the hooked ends of the bolts 16 engaged with a bead 22 formed on the top edge of the tub 24, which is illustrated as of circular form, but it is obvious that the cover is adapted to be secured to receptacles of other sizes as well as of other forms or shapes, since the adjustment of the bolts enables them to be shifted to correspond to the location of the points of attachment on the receptacle.

Mounted within the opening 8 of the cover member is a washing cylinder comprising a pair of spaced side plates or disks 26 which are connected by a cylindrical drum 28 of corrugated material which may be suitably soldered to the disks 26. The drum is provided with sets of perforations 30, and also is doubled inwardly at two or more points to form the radial flanges 32 extending longitudinally of the cylinder and adapted to engage the clothes within the drum whenever the latter is rotated. The cylinder is provided with a hinged door 34 for the insertion or removal of the contents of the cylinder, said door being formed by a hinged section of the drum 28 which is pivoted on a bolt 36 and adapted to be latched by means of a bolt 38 (see Figs. 2 and 3). The outer faces of the disks 26 are provided with central trunnions 40 and 42, respectively, journaled in suitable bearings 43 on the angle pieces 12, the trunnion 42 being elongated to form a shaft extending beyond the outer edge of the cover member 6 where it is provided with a suitable operating handle 44.

The arrangement of the angle pieces 12 and 14 provides upstanding flanges within which to position and seat a semicircular housing 46 of a size sufficient to inclose the upper half of the washing cylinder, said

housing being provided with a handle 48 for use in removing or replacing the housing in the position illustrated in Figs. 1 to 3.

It will thus be apparent that a simple and efficient arrangement and construction have been devised for carrying out the desired objects of the invention. The cover member, with its securing means arranged as above described, is of such a character as to adapt 10 the same to be removably secured in position over different sizes and shapes of receptacles; for example, the cover may be secured to tubs such as shown but of varying diameters, or to a wash boiler of the common 15 well-known type, the slots 20 permitting the bolts 16 to be shifted to the required positions of adjustment for securing the same to the top margin of the receptacle. When 20 thus secured, one half of the washing cylinder projects down into the tube or receptacle in the usual operative position where it is submerged partially in the wash water as 25 illustrated in Figs. 2 and 3, while the upper half of the cylinder is inclosed by the housing 46 which guards against the escape of fumes, steam, etc. When the wash cylinder 30 is supplied with clothes to be washed and is rotated by operation of the handle 44, the water and steam may enter the cylinder 35 through the perforations 30, and the flanges 32 serve to pick up and carry the contents of the cylinder part way around with the drum 28, said contents dropping back down soon 40 after the flanges pass horizontal position. 45 The corrugated surface of the drum 28 acts with the ordinary washboard effect upon the contents of the cylinder to enhance the cleaning action, as will be readily understood.

While I have illustrated and described what I now regard as constituting the preferred form of embodiment of the improvements, I desire to expressly reserve the right 40 to make all such formal changes or modifications as may fairly fall within the scope of the appended claims. 45

What I claim is:

1. In a washing machine, a cover adapted to be secured to a receptacle, a rotary cylinder journaled on said cover, a housing for said cylinder, and adjustable securing means 50 for attaching said cover to various sizes of receptacles.

2. In a washing machine, a cover adapted to be secured to a receptacle, a rotary cylinder carried by said cover, a housing carried by the upper face of said cover, said cylinder being journaled on said cover so that one half of said cylinder is inclosed by said housing and the other half of the cylinder projects below said cover, and adjustable securing 55 means for attaching said cover to various sizes of receptacles. 60

3. In a washing machine, a cover adapted to be secured to a receptacle, a rotary cylinder journaled on said cover with one half of 65 the cylinder projecting beneath the cover, a removable housing for the upper half of said cylinder, said cover being provided with a series of attaching bolts and slots adjustably receiving said bolts, whereby said cover may 70 be detachably secured to different sizes of receptacles.

In witness whereof I hereto affix my signature.

ERNEST M. WENZEL.
